UNITED STATES PATENT OFFICE.

ISAAC HAYES, OF PHILADELPHIA, PENNSYLVANIA.

APPARATUS FOR VAPORIZING AND BURNING NON-EXPLOSIVE OILS FOR HEATING PURPOSES.

SPECIFICATION forming part of Letters Patent No. 394,179, dated December 11, 1888.

Application filed January 16, 1888. Serial No. 260,950. (No model.)

To all whom it may concern:

Be it known that I, ISAAC HAYES, a citizen of the United States, residing in the city and county of Philadelphia, and State of Pennsylvania,

have invented a new and useful Improvement in Apparatus for Vaporizing and Burning Non-Explosive Oils for Heating Purposes, of which the following is a specification.

10 The object of my invention is to provide an apparatus wherein any of the non-explosive or heavy oils—such as astral or head-light oil—may be vaporized and burned to create heat for any purpose where a ready and reliable heat is required.

15 My invention consists of a suitable metal box or frame in which are arranged longitudinally a double return system of tubes and flues, through which the oil is allowed to flow and become vaporized by previously introducing and igniting a small quantity of naphtha in the box sufficient to heat the tubes.

20 Reference is had to the accompanying drawings, in which Figure 1 is a perspective view of my invention. Fig. 2 is a vertical transverse section on the line *a b* of Fig. 1. Fig. 3 is also a vertical transverse section on the line *c d* of Fig. 1. Fig. 4 is a perspective view of my invention, showing it applied in the fire-box of a cooking-range.

25 A is a cast-metal box or frame of rectangular form, of any suitable dimensions, made concave inside, with the base recessed from the points *e* to *f*, Fig. 1, in which is secured a curved sheet-metal scattering-plate, B, with an intervening space for the passage of flame.

30 C and C' are tubes extending longitudinally through the interior of the box A on each side and within a short distance of the top, and communicating with lower return-flues or tubular passage-ways, D and D', made longitudinally through the solid metal of the box.

35 C² and C³ are vertical tubes located on top and near each end of the box, with their lower ends secured in the orifice of openings E and E', which extend downward and connect at right angles with the flues D and D', Figs. 1 and 3. Secured to the upper ends of the said tubes C² and C³, and projecting hori-

zontally from the same, are two overhead superheating-tubes, C⁴ and C⁵, provided at their opposite extremities with downward-projecting burners G and G'.

40 The outer ends of the tubes C and C', which project through the opposite ends of the box, may join and lead to any suitable reservoir containing non-explosive oil, while the inner ends connect with the lower flues, D and D', through vertical passages F and F', made in the metal at the opposite ends of the box, as shown at Figs. 1 and 3. The oil flowing through the tubes in the direction shown by arrows, Fig. 1, is first heated to generate vapor by igniting a small quantity of naphtha within the box; or naphtha in a limited quantity may be supplied from a small reservoir, after which the flame from the burning vapor of the non-explosive oil will continue to heat the tubes and flues.

45 e and e', Figs. 1 and 2, are small apertures made through the bottom of the box A, directly below the burners G and G', through which a portion of the flame passes and impinges the scattering-plate B, by which means the flame is caused to circulate freely around the sides of the box.

50 The edges of the metal in the recesses at the base of the box and around the flues D and D' are rounded off, and the outer edges of the plate B are correspondingly curved to direct a portion of the flame passing through the apertures *e* and *e'* upward and closer around the flues, as shown in Fig. 2. The flame also impinges the interior concave sides of the box, and is turned upward to completely surround the upper tubes, C and C', thus causing the heat to vaporize the oil readily. The overhead tubes C⁴ and C⁵ are also subject to the action of the flame ascending from the interior of the box, by which means the oil or vapor within them is superheated, thereby causing a more complete combustion at the burners.

55 My invention may be applied in the fire-box of a cooking range, stove, or heater, either above or below the grate; or the grate may be removed and the fire-box arranged with cross-bars to support the apparatus, as shown in Fig. 4.

60 I do not wish to limit myself to the exact number of tubes and flues used, as two or

more may be employed. Nor do I wish to confine myself to the exact construction herein described, as slight modifications may be made in the direction of the apertures and flues, and the oil may be admitted at one end of the box by extending the passages or openings to connect the flues and upper tubes.

What I claim, and desire to secure by Letters Patent, is—

10 The combination of the box A, provided

with longitudinal flues D and D', openings E and E', vertical passages F and F', apertures e e', with the tubes C, C', C², C³, C⁴, and C⁵, burners G and G', and scattering-plate B, substantially as and for the purpose herein specified.

ISAAC HAYES.
